UNITED STATES PATENT OFFICE

THEODORUS WILLEM MUNDT, OF BILTHOVEN, NETHERLANDS

TURNTABLE

Application filed April 22, 1929, Serial No. 357,300, and in Germany June 16, 1927.

Owing to the constant increase in the size and weight of locomotives, the old method of construction of turntables, in which the main girders are supported only in the middle, has 5 been abandoned and new methods of construction have been introduced.

The new constructional forms, of which those with subdivided and those with continuous main girders have been more generally adopted, do away with the recognized faults of the old constructional forms (bumping when the wheels of the leading axle run on to the turntable, the necessity of balancing the locomotive as accurately as possible before the turntable can be turned, high main girders and a correspondingly deep pit, and so on), by the wheels at the girder ends resting on the race and taking up a portion of the load.

20 The turntables with subdivided main girders, however, in most cases do not turn with the same ease as the older constructions. They have the further disadvantage that they are relatively complicated, owing to the 25 pivotal connection of the two halves of the main girders, while there is difficulty in making them rigid in the horizontal direction without the provision of special means, which may easily cause trouble more particularly in 30 turntables of large diameter.

In the turntables with continuous main girders as at present made, the cross-section of the main girders is designed in accordance with the greatest bending moment, the main 35 girders having a constant moment of inertia over their entire length, or the main girders are tapered towards the ends. In order that the turntable shall move easily, it is necessary that the greater part of the load shall 40 rest on the centre support, for which purpose this support should be placed as high as possible with respect to the peripheral supports.

In order further that the turntable shall 45 turn as easily as possible, with the desired position of the rails in a horizontal plane, the centre support must therefore be placed so high that the main girders may be designed as continuous straight girders resting on three points of support of equal height and equidistant from one another.

If the girders have a constant moment of inertia or if they be tapered towards the ends, the end of the unloaded arm will tilt upwards, when the turntable is loaded on one side by a heavy locomotive, independently of whether 55 the moment of inertia is great or small. Hence it was necessary in turntables with continuous main girders to place the centre support so much lower than the peripheral supports that with the greatest one-sided load 60 to be expected the end of the unloaded arm would not tilt upwards. In view of the inequalities in the height of the roller race, which are unavoidable in laying the race and during the operation of the turntable, the 65 centre support must be placed still lower than would be necessary theoretically. This not only sacrifices the easy running of the turntable, but also increases the maximum bending moment so that the cross-section of the 70 girders must be designed to allow for this greater bending moment and the girders, owing to their rigidity, will not readily adapt themselves to the unavoidable inequalities in 75 the height of the race.

In order not further to endanger the easy running of the turntable, the centre support is in some cases placed so low that with the greatest inequality in the height of the race to be expected in ordinary practice, the end 80 that is unloaded shall barely avoid tilting up, when the turntable is loaded on one side. This, however, causes the adhesive pressure or tractive force at the unloaded end to be insufficient, so that it is impossible to drive the 85 turntable at this point only.

Consequently, turntables with continuous main girders are almost all driven at both ends, which is complicated and uneconomical. Where, however, a drive on one side only has 90 been provided, it is impossible to turn the turntable, when it is loaded only on the side lying opposite the drive, or at least it becomes so difficult in view of the necessity of still further lowering the centre support that where the turntable is driven by hand the operation takes too much time.

When a continuous girder resting on three points of support of equal height and equidistant from one another is loaded on one 100

side and its unloaded end tilts up, this tilting may be prevented by the provision of reinforcements of the cross-section externally of the centre support.

5 The object of the invention is to apply this principle to the design of turntables, so that all the disadvantages of the older system are done away with, a one-sided drive will suffice and easy running is ensured.

10 The cross-section of the continuous girders on three points of support of equal height is determined in accordance with the greatest negative bending moment occurring above the centre support, while, for taking up the greater positive bending moment, the cross-section is strengthened externally of the centre support, which may be effected in the simplest manner, for instance by attaching plates or, in the case of riveted girders (if the booms 20 are to remain unaltered), by increasing the height of the web.

15 In most cases an increase in the strength of the cross-section, in order that the greater positive bending moment may be taken up, will be sufficient to prevent the unloaded end from tilting up when the supports are of equal height, and, the turntable is loaded on one side, thereby making it possible to adopt a one-sided drive.

20 Should the possible one-sided load be so great that the frictional or adhesion pressure between the drive wheels and the track is insufficient for a one-sided drive, the frictional or adhesion pressure can be made sufficient by strengthening the cross-section externally of the centre support or by placing the centre support somewhat lower.

25 The adoption of the construction according to the present invention enables the material to be distributed in the most favourable manner. Furthermore, as the girders are less rigid in the vertical direction than those of the older constructional forms with continuous main girders, the construction adapts 30 itself well to the unavoidable inequalities of the race. As compared with turntables of a known kind having subdivided main girders, the construction according to the present invention is simpler and cheaper, as no linked joint is required. In addition to this, whatever the loading conditions, the total wheel pressure is considerably lower, so that the turntable will turn far more readily. As compared with the older turntables with continuous girders, the new construction has this 35 advantage that, whatever the loading conditions, a one-sided drive on one side of the centre line of the track will suffice and that the distribution of material in the main girders is a logical one, so that the construction adapts itself more readily to any changes in the relative height of the three supports.

40 A constructional example of the invention is illustrated in the accompanying drawing, in which Fig. 1 is a diagrammatic representa-

tion and Fig. 2 a cross-section through the centre support.

45 In Fig. 1 of the drawing T is one of the main girders which extends unbroken over the sections or radial fields 1 (measured from the center of the end bearings to the center support). The main girder is provided outside the centre support, in the fields 1 up to the points of zero moment, over a length a with reinforcing plates b , in order that the greatest bending moment may be taken up and so that for all loads, the frictional or gripping pressure will be sufficient for a motor drive at one girder end and to one side of the centre line of the track. According to Fig. 2 the two main girders T, which are connected by transverse bracing, rest on the annular upper part or cap c of the king post, from which a guiding ring d or apron extends into the lower part or base e . The upper part or cap c is journaled by means of a ball race bearing f on the lower part or base e . The guiding ring or apron d transmits the horizontally acting forces from the upper part or cap through a ball or roller bearing g to a centering spindle h which is rigidly fixed to the lower part or base but does not bear any weight.

50 The height of the centre support c can be adjusted in any suitable manner, for instance by introducing or removing gaskets or packing pieces.

55 Each end of the main girder is supported by a pair of head bearings which are provided with rollers. The turntable may be driven by means of a motor or by hand, at one end of the girder only and to one side of the centre line of the track.

60 What I claim is:

1. In a turntable, a pair of continuous 105 girders of substantially uniform cross-section suitably interconnected, central and end supports, reinforcing plates for said girders extending from said end supports short of the center support in order to provide rigidity 110 of the girders against bending forces for the entire length of said plates, while permitting bending between the inner ends of said plates.

65 2. A turntable comprising suitably interconnected main girders of substantially uniform cross section, end supports for the girders and a center support therefor, reinforcing elements for the girders positioned in a section thereof where bending stresses are greatest and extending to points of zero moment, thereby permitting bending of the structure between said points thus insuring sufficient tractive pressure at the end supports for operating the turntable from either end.

70 3. In a turntable constructed for obtaining moments of inertia of different magnitude in the portions thereof situated on either side of a center support; said turntable having continuous main girders resting on three points 120

of support and forming a structure of un-
weakened cross-section, reinforcing plates
extending inwardly from the outer supports
to within a certain distance of the center sup-
port thereby stiffening the structure except
between the inner ends of said reinforcing
plates, thus permitting sagging of the ends
of the structure over said end supports there-
by permitting the turntable to be driven from
one end thereof.

In testimony whereof I affix my signature.
